UNITED STATES PATENT OFFICE.

LAFAYETTE J. ALLIE, OF ST. PAUL, MINNESOTA.

FLUE-STOPPER.

1,401,936.

Specification of Letters Patent. Patented Dec. 27, 1921.

Application filed February 24, 1920. Serial No. 360,807.

To all whom it may concern:

Be it known that I, LAFAYETTE J. ALLIE, a citizen of the United States, residing at St. Paul, in the county of Ramsey and State 5 of Minnesota, have invented a new and useful Improvement in Flue-Stoppers, of which the following is a specification.

My invention relates to improvements in flue stoppers and is particularly adapted 10 for use in connection with a chimney flue where it is desirable to close the flue opening when the pipe is removed from the thimble to form a closure with a neat outer appearance.

15 A primary feature of my invention is in a simple device which is readily collapsible for packing and shipping and is provided with means for firmly anchoring the closure, over the outer end of the thimble opening so 20 that it will not easily become misplaced but will be held with its periphery snugly about the outer edge of the thimble opening.

25 A further object of the invention is to provide anchoring means for the closure which will have a tendency to draw the closure tight over the flue opening. When the anchoring means is set in holding position it is so constructed as to engage the inner surface of the flue opening at an angle 30 and under spring tension, causing the engaging ends of the anchoring means to tend to bite into the inner surface of the flue opening. While the releasing means in connection with the anchoring element engages 35 the closure axially, tending to draw the same tightly over the outer end of the flue opening. The stopper can be readily removed from the flue opening by releasing the anchoring means.

40 In the accompanying drawing:

Figure 1 illustrates the inner face of the flue stopper with its closure and anchoring means.

Fig. 2 is a vertical cross section of the 45 stopper in connection with a thimble and flue opening, partly illustrated in longitudinal section.

Fig. 3 is a vertical section of the stopper, 50 illustrating the normal position of the anchoring means.

Fig. 4 is a vertical section of the closure portion of the stopper in connection with the anchoring and releasing means as they

would appear in knocked-down or collapsed position for packing.

Fig. 5 is an inner view of an alternative construction of my stopper.

The drawing illustrates the stopper A, which is adapted for use particularly as a flue stopper, but it will readily be seen that the stopper can also be used for other purposes to form a closure for an opening. The stopper A is formed with a suitable circular closure 10, which is of ordinary construction, to which are attached bracket arms 11 60 by rivets or other suitable attaching means. The arms 11, when attached to the closure 10, lie flat against the same, excepting that they are provided with scores 12 so that when their outer free end 13 is engaged the bracket 70 arms can be bent into the position illustrated in Figs. 2 and 3. It is most desirable to have the arms 11 lie flat or approximately so against the inner surface of the closure 10, to which they are attached, before the 75 stopper A is set up and put together for use so that it can be readily packed for shipment or storage and this forms an important feature of my invention.

The free ends 13 of the arms 11 are provided with openings 14, through which the engaging ends 15 of the spring anchoring element 16 project when the bracket arms 11 are bent at approximately right angles to their attached ends and the inner surface 85 of the closure 10.

The spring anchoring element 16 is centrally engaged between its ends by the operating bolt 17, which is adjustably attached by the nuts 18 to the anchoring element 16 90 on one end and is provided with an engaging head 19 on the other end, which is formed with a stop shoulder 20.

The engaging head 19 projects from the outer surface of the closure 10 while the 95 operating end of the bolt 17, which engages the anchoring element 16, extends through the closure axially and the shoulder 20 is adapted to engage the outer surface of the closure when the anchoring element 16 is 100 moved into locking position, as illustrated in full lines in Fig. 2.

In the use of the stopper A as a flue closure, the head 19 is engaged and pulled outward slightly to withdraw the engaging 105 ends 15 of the spring anchoring element 16

sufficiently to allow the anchoring means of the stopper to be inserted freely into the thimble or flue opening B. When the closure of the stopper is in place against the 5 outer surface of the flue opening, the operating bolt 17 is pressed inward, which causes the engaging ends 15 to move from the dotted position, illustrated in Fig. 2, to the full line position, in the direction of 10 the arrow. This movement of the engaging ends 15 causes them to scrape along the inner surface of the flue opening B, tending to draw the closure 10 tightly against the outer opening of the flue opening, while 15 when the shoulder 20 comes into engagement with the outer surface of the closure, the anchoring element 16 will hold the closure in closed position under spring tension with the ends 15 having a tendency to bite 20 into the inner surface of the flue opening B. This feature is desirable in the operation of a flue stopper, as it tends to draw the closure of the stopper more tightly into closed position and always holds the same in 25 closed position under spring tension. Thus the stopper will not readily become misplaced or jar loose.

The spring anchoring element 16 is adapted to normally extend straight or flat, as 30 illustrated in Figs. 3 and 4, and its length being somewhat longer than the inner diameter of the flue opening in which it is adapted for use, causes it to be moved into a bowed position when in anchoring position or when it is being inserted. The free 35 ends of the element 16 are formed with shoulders 21, which engage against the arms 11 slightly when the element is in released position, as illustrated in Fig. 3. These 40 shoulders 21 have a tendency to center the spring element 16 and prevent it from becoming easily misplaced.

Fig. 5 illustrates the spring element 16' formed with four engaging ends from a 45 single piece of spring material, which is provided with flue engaging ends 15. This construction provides double the amount of engaging and holding strength to the stopper A but the functions of the element 16' are 50 exactly the same as that of the single arm, which is only provided with the two engaging ends. The element 16' is operated in the same manner by the bolt 17.

The operating bolt 17 is rigidly attached 55 to the element 16 by the nuts 18 and is adjustable by the same so that the bolt 17 can be properly positioned and connected to the spring anchoring element 16. On the other hand, when it is desired the stopper 60 A can be collapsed by disengaging the member 17 from the member 16 and the free ends of the bracket arms can also be bent back flat against the inner surface of the closure 10. In fact, these bracket arms can 65 be bent several times without injury to the

same if they are made of the proper material. It is also a feature of the invention that the spring anchoring element 16 can be replaced at any time by a new similar element if it is desired.

The angular, bowed position assumed by the anchoring element 16 when it is moved from the dotted position into locking position, as illustrated in full lines in Fig. 2, 75 will readily set forth the efficient manner in which the anchoring means of the stopper A hold the same in closed position and it is evident that the stopper can be readily removed from the flue opening by engaging the head 19 and pulling the same outward, 80 which releases or unlocks the engaging ends 15. When the stopper A is collapsed it is very compact, thus making it more easy to handle for shipment or storage or to be handled in the stores where they are offered for sale. The inexpensive, simple construction gives a device of a practical nature.

In accordance with the patent statutes I have described the principles of operation 90 of my invention and while the construction illustrated is of a particular form, I do not wish to confine myself to the exact device illustrated but desire to have it understood that my device can be applied to uses other 95 than those above set forth within the scope of the following claims.

What I claim is:

1. A flue stopper comprising a closure member, a pair of outwardly extending 100 brackets adapted to be folded back into the plane of said closure member, and a normally planiform spring member adapted to coöperate with said brackets for securing the stopper within a flue opening.

2. A flue stopper comprising a closure member, supports on said closure member, a one-piece normally planiform spring member of a dimension greater than the diameter of the flue opening mounted on 110 said supports, said spring member being adapted to be arched toward the closure member upon insertion into the flue opening and to be arched away from said closure member to secure the stopper within a flue.

3. A flue stopper comprising a closure member, supports on said closure member, a one-piece normally planiform spring member of a dimension greater than the flue opening and mounted on said supports, 120 and means for arching said spring member toward said closure member for permitting insertion of the stopper within a flue opening and for reversing the arching of said spring away from the closure member to 125 cause said closure member to be drawn into the flue opening and secured therein.

4. A collapsible flue stopper, comprising a closure and anchoring means adapted to be collapsed into a flat, compact state when not 130

in use, said anchoring means including a closure, a normally planiform, normally planiform, spring engaging or anchoring element.

5. A flue stopper, including a closure, bracket arms attached normally planiform against said closure, a flat, spring anchoring element, an operating bolt for said element and scores formed in said bracket arms to allow the free ends to be bent to project from 10 the inner surface of said closure to receive said spring anchoring element and said operating bolt being adapted to be connected to said anchoring element to form a closure for the purposes specified.
- 15 6. In a device of the class described, including a closure and a spring anchoring element freely attached to said closure and adapted to hold said closure against an opening under spring tension.
- 20 7. In a device of the class described, in-

cluding a closure, a normally planiform, normally planiform, spring anchoring element and means for attaching and operating said element to hold said closure in closed position over an opening.

- 25 8. In combination with a flue thimble a flue stopper comprising a closure member, supporting means secured on said closure member, means movable and supported by said supporting means and having an engaging end adapted to engage the flue thimble along its inner surface, and means for moving said engaging means when the stopper is inserted relative to said closure member along said thimble in a direction 30 toward said closure member to cause the closure member to be drawn inwardly tight 35 against the edge of the thimble.

LAFAYETTE J. ALLIE.
